UNITED STATES PATENT OFFICE.

NELS AUGUST VELINE, OF VILLISCA, IOWA.

CARPET-STRETCHER.

SPECIFICATION forming part of Letters Patent No. 291,555, dated January 8, 1884.

Application filed November 12, 1883. (No model.)

To all whom it may concern:

Be it known that I, NELS AUGUST VELINE, a citizen of the United States, residing at Villisca, in the county of Montgomery and State 5 of Iowa, have invented certain new and useful Improvements in Carpet-Stretchers; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 My invention has reference to certain improvements in stretching and holding in place carpets; and it consists, essentially, in placing permanent rollers on the floor around the margin of the room, such rollers being provided 20 with teeth or short hooks to engage and hold the carpet, as hereinafter more fully described.

In the drawings, Figure 1 is a plan view of the carpet as held in stretch by my invention. Fig. 2 is a detached view of a section of the 25 roller and its ratchet-wheel. Fig. 3 is a detached view of the lever used to rotate such roller. Fig. 4 is a sectional end view of the roller, showing the hook in place and the conformation of its shank.

30 A is the carpet in stretch.

B B B B are the walls of the room.

CCCC are the rollers in position, such rollers being made with half-round, oval, or square sides, or some shape other than round.

35 D D are the hooks, which are formed, respectively, with the shanks E integral therewith. The opening E' in the shanks E is made to conform to the lateral shape of the rollers C, so that when such rollers are passed through

40 such shanks the hooks, although attached to the carpet, shall be free to move laterally on such rollers, so as to permit the carpet to be stretched in a transverse direction. By reason of the sides of the rollers having an irregular

45 shape and the shanks E conforming thereto in the rotation of the rollers C, the hooks D are rotated therewith; but the latter are free to move in the line of the rollers C, so as to prevent the wrinkling of the carpet when the

50 latter is drawn at right angles to such roller, in order to stretch the carpet in a cross or transverse direction in the room. The hooks D are

made short, so as to readily pass with the carpet outwardly under the roller C and next the floor. The rollers C are held in position by 55 being journaled at suitable intervals in the bearings H, which latter encircle the rollers C at their front end, and at their rear end are provided with a shank, by means of which latter the bearings H are suitably attached to the 60 wall of the room sufficiently above the floor to permit the passage under the bearings of the carpet A. The journaling of the rollers C countersinks the bearings H below the general 65 surface of such rollers, so as to leave the surface of such rollers uniform. Each roller is provided at one end with a ratchet-wheel, L, rigidly affixed thereto for the purpose of rotation, and a pawl, a, fastened to the wall, which engages such ratchet-wheel and holds the roller 70 from reverse rotation. A detachable lever, M, fitted to engage and actuate the ratchet-wheel L, is used to rotate the rollers C, as desired. It may be necessary to place the rollers C on but two sides of the room at right 75 angles to each other, the carpet being first tacked on the two opposite sides, in which case the rollers should be placed on those sides of the room in which there are no doors; but the rollers may be placed on all sides of the 80 room, the carpet being tacked at the door-openings after it is stretched by the rollers. The rollers can be made of small diameter and placed out of sight under the bottom or behind the base-board, a small opening being 85 left at the corner of the room or other obscure point for the insertion of the end of the lever M. As the carpet stretches with use, the rollers can be tightened, and thus the carpet kept 90 smooth and tight at all times.

The mode of operation is very simple. The carpet is attached to the hooks D on both sides of the room and gradually tightened by successively or simultaneously rotating all of the rollers C by means of the lever M. The edges 95 of the carpet are concealed under the base-board, which makes a neat and very pleasing appearance.

By releasing the pawl a, the rollers C can be rotated backward and the carpet readily 100 unhooked and taken up when desired.

The hooks D should be of sufficient number and frequency to properly stretch the carpet without tearing or injuring it.

The advantages of my invention are, first, the convenience of laying down and taking up the carpet; second, the means afforded for re-stretching the carpet at any time without taking it up; third, a more uniform stretching than is possible where the carpet is directly fastened to the floor upon all sides; fourth, a simultaneous stretching of the entire carpet before any of it is fastened permanently, as distinguished from a partial stretching in a succession of efforts at different points; and, fifth, the neat appearance attained by concealing the edges or margin of the carpet.

What I claim as my invention, and desire to secure by Letters Patent of the United States, is—

1. The rollers C, provided with hooks D and

ratchet-wheel L, and suitably journaled in bearings H, substantially as shown, and for the purpose described.

2. The combination of the rollers C, provided with ratchet-wheel L, the hooks D, and bearings H, substantially as shown, and for the purpose specified.

3. The combination of the rollers C, provided with the ratchet-wheel L, the hooks D, bearings H, and lever M, substantially as shown, and for the purpose mentioned.

In testimony whereof I affix my signature in presence of two witnesses.

NELS AUGUST VELINE.
